FILTER

Gustaf Einar Lofgren, Riverside, Conn., assignor
to Electrolux Corporation, Dover, Del., a cor-
poration of Delaware

Application September 2, 1937, Serial No. 162,103

4 Claims. (Cl. 183—49)

My invention relates to filters and more particularly to a filter for use with vacuum cleaners.

An object of my invention is to provide an improved filter for use with vacuum cleaners, providing a relatively large area for efficiently removing the dirt from the air and without, at the same time, producing a large back pressure.

What I consider to be novel and my invention may be better understood by reference to the following specification and appended claims when considered in connection with the accompanying drawing, in which

Fig. 1 is a side view of a vacuum cleaner broken away to show the filter;

Fig. 2 is a top view of the filter frame;

Fig. 3 is a side view of the frame;

Fig. 4 is a side view of the frame and one of the filter coverings;

Fig. 5 is a side view of the completely assembled filter and

Fig. 6 is a side sectional view of the assembled filter.

In the drawing, 10 indicates a vacuum cleaner having an inlet suction opening 11 at one end and an outlet opening 12 at the opposite end. In normal use as a suction cleaner, dirt laden air enters through opening 11 and most of the dirt carried thereby is deposited in a bag, not shown.

There may be fine particles of dust which are not separated from the air by the bag and to prevent this fine dust from passing out the outlet opening 12 into the atmosphere and also to catch any carbon dust from the motor brushes, a filter 13 is provided and located adjacent the opening 12. As better indicated in Figs. 2 and 3, a metal frame 14 is provided substantially of cylindrical form or cup shape with a depression 15 formed at one end by inwardly projecting arms

16 integral with the body of frame 14. Projecting from the opposite end of frame 14 are fingers 17 with inwardly extending radial projections 18. These fingers 17 are adapted to secure the filter 13 to a housing 19 located adjacent the opening

12 by means of the projections 18 which snap into an annular recess 20 in the housing 19. A shoulder 21 of the frame 14 adjacent the fingers 17 serves as a stop in the mounting of filter 13 on housing 19. The frame 14 is cut away at its end and sides to present a minimum of obstructing surface to the passage of air, at the same time providing a substantially rigid construction.

The shape of the frame 14 with its cylindrical form or cup shape having considerable depth, presents a much larger filtering area than the

conventional disc shaped filters. Any desired cross-sectional shape can be used with a corresponding depth to provide the required filtering area. With a large area, a greater amount of air can be passed through the filter with a lesser drop in pressure or, in other words, a lower back pressure than would be produced by filtering with a smaller area.

To filter the dust from the air, filtering material consisting of two layers of fabric 22 and 23 are located around the frame 14 as best indicated in Fig. 4. The layer of fabric 22 consisting of a plurality of layers 24 of felted fibers, such as cotton, backed by a cloth 25 of coarse weave is formed in a rectangular shape and wound around the cylindrical part of frame 14, spaced a short distance from the open end portion of the periphery of the frame. The cloth 25, in addition to serving as a backing for the layers 24 of fibers, due to its location on the inside of fabric 22 prevents the fibers from being carried out with the air through outlet opening 12. Prior to the application of fabric 22, frame 14 is covered with a sticky substance for securing the fabric to the frame. The portion or excess of the fabric 22 extending beyond the end or the cylindrical height of the frame 14 is loosely tucked in the depression or recess 15 of the frame 14 as best indicated in Fig. 6. It may be desirable in some cases to pre-form the fabric 22 with a folded end and then secure it to the frame 14. However, it is more economical as a manufacturing process to wind a fabric of rectangular shape around the frame securing it at one end and then folding the free end of the fabric around the opposite end of the frame. The folded end of the fabric 22 provides a plurality of layers of fabric through which the air passes. Each layer of fabric 22 consists of a plurality of layers 24 of fibers and a layer of cloth 25. Each one of these layers provides a surface on which dust may be deposited. A single layer would soon be clogged with dust that could easily be deposited on these plurality of layers of material without interfering with the passage of air therethrough. Either fabric 22 or fabric 23, or both, may be impregnated with a substance for purifying the air as it passes through it. The fabric 23 is formed in a shape conforming substantially to the shape of the frame 14. It is secured to the frame 14 by means of a sticky or gummy substance placed on the portion of the frame 14 uncovered by the covering 22. The covering 23 serves to hold the covering 22 with its loosely folded end in depression 15. Any tendency for the covering 22 to

loosen up or unfold in the depression 15 of the frame 14 which would reduce its effectiveness as a filter by permitting air to flow between its folds, is prevented by the covering 23. Covering 23 also 5 serves as an additional layer of material upon which dust may be deposited as the air passes through filter 13.

When the member of layers of material comprising a filter element is increased the resistance 10 to the flow of air therethrough is increased but this increase in resistance may be offset by an increase in the filter area. Thus, by providing a filter having a considerable depth, a plurality of layers of filtering material may be used to increase the efficiency of the filter without increasing the resistance to the flow of air. In addition, the plurality of layers of filtering material act as a sound deadening material and reduces the amount of noise that passes through the filter. 15 In this manner less of the noise produced by the motor and other means within the vacuum cleaner is transmitted to the outside through the outlet opening 12.

Whenever the fabric 22 or the fabric 23 becomes so clogged with dust as to greatly reduce the flow of air through it, it may be removed from the frame 14 and a new or clean fabric substituted therefore.

From the foregoing, it may be seen that an improved filter is provided presenting a relatively large area with many layers of filtering material, which is of relatively simple construction and may be economically manufactured.

What I claim is:

1. A filter comprising a frame of substantially cylindrical form having a depression at one end,

a covering of fabric of a length to extend beyond the cylindric height of said frame, said covering being secured around the periphery of said frame and the excess length of said fabric being loosely folded in said depression, and an outer covering of fabric secured to said frame and enclosing said first-named covering. 5

2. A filter comprising a frame of cup shape having openings in its sides and ends, a covering of fabric for said side openings of a length to extend 10 beyond the end of said frame, said cover being loosely folded over one end, and an outer covering of fabric secured to said frame and enclosing said first-named covering.

3. A filter comprising a frame of substantially 15 cylindrical form having inwardly extending arms at one end forming a concave recess, fingers formed integrally with said frame extending from the end opposite said last-named end and having inwardly extending projections, a covering of 20 fabric of a length to extend beyond the cylindric height of said frame, said covering being secured around the periphery of said frame and being loosely folded in said recess, and an outer covering of fabric secured to said frame and inclosing said 25 first-named coverings, said fingers being adapted to secure said frame to a support.

4. A filter comprising a box-like frame, a plurality of layers of fibers backed by cloth of a length to extend beyond one end of said frame, said 30 cloth being secured to the outer periphery of one end of said frame and the excess length of said cloth being loosely folded over the other end of said frame, and a second covering of fabric secured to said frame. 35

GUSTAF EINAR LOFGREN.
